UNITED STATES PATENT OFFICE.

EDSELL T. BLEECKER, OF PUEBLO, COLORADO.

DESIGN FOR A BOX OR SIMILAR RECEPTACLE.

Application filed July 10, 1928. Serial No. 27,438. Term of patent 7 years.

To all whom it may concern:

Be it known that I, EDSELL T. BLEECKER, a citizen of the United States, residing in Pueblo, in the county of Pueblo and State of Colorado, have invented a new, original, and ornamental Design for a Box or Similar Receptacle, of which the following is a specification, reference being had to the accompanying drawings, forming a part thereof.

In the drawing, the figure represents a box or similar receptacle showing my design.

I claim:

The ornamental design for a box or similar receptacle, as shown.

In testimony whereof I have affixed my signature.

EDSELL T. BLEECKER.
